UNITED STATES PATENT OFFICE.

CYRIL FREDERICK BIGMORE, OF LONDON, ENGLAND.

MECHANICAL RACE-GAME APPARATUS.

Application filed February 14, 1921. Serial No. 444,900.

(GRANTED UNDER THE PROVISIONS OF THE ACT OF MARCH 3, 1921, 41 STAT. L., 1313.)

To all whom it may concern:

Be it known that I, CYRIL FREDERICK BIGMORE, a subject of the King of Great Britain and Ireland, residing at 1 Ravensdale Mansions, Haringey Park, Crouch End, London, N. 8, England, have invented certain new and useful Mechanical Race-Game Apparatus, of which the following is a specification.

10 This invention relates to a mechanical race game apparatus of the kind in which a moving band is provided upon which racing figures such as the figures of race-horses may be disposed in line and obstructions provided in a position over the band so that thus as the band moves forward, the progress of the figures may be hindered to a varying degree by the obstacles presented, the bases of the figures 15 being of a form adapted to enable them to pass over the obstacles while being carried forward by the moving band.

The invention relates to improvements comprising obstructions in the form of transversely disposed wires, and an improved base for the racing figures, adapting them 20 with such obstructions.

The invention comprises the construction hereinafter described.

30 In carrying the invention into effect, an endless band of felt for example a foot wide may be mounted upon and between parallel disposed rollers carried at the respective ends of a supporting frame. This 35 supporting frame may have disposed on each side a series of posts and other details for the more complete representation in miniature of a race-course. A series of obstacles are transversely mounted upon the 40 frame above the top part of the endless band comprising wires transversely disposed across the frame so as to lie over and in proximity or in contact with the top part of the travelling band. In addition a number 45 of obstacles of different forms may be provided such as obstacles of a substantially angular or ridge form of any transverse section, the lower edges of the ridges lying over and in contact or proximity to the top 50 part of the travelling band.

These last mentioned obstacles may represent hedges while other obstacles may be provided to represent hurdles.

The racing figures are provided with bases 55 of such form as to be capable of riding over

the obstacles. For this purpose the base is advantageously made heavy and its front part is curved upwardly so that, as the band moves, the respective figures ride over the wires and ride up the ridges or other obstacles. In a middle position or towards the rear the base of the racing figure is hollowed out on its under-side or otherwise formed so that the rear edge protrudes downwardly, and so that thus as the figures ride up the wires or other obstacles on the upwardly moved front end, the rear edge beds into the felt so that thus the figure is carried by the travelling band completely over the ridge or obstacle. Where the wires or the ridge or other obstacle is of substantial height such for example as one-eighth inch or one-quarter inch, the figure on passing over the ridge or obstacle falls forward so that the curved front part of its base then falls on to the felt or band in front of the ridge and thus is drawn forward by the band completely over the ridge, the formation of the rear under-face of the base in the manner described facilitating this operation. To ensure that the figures may be readily moved by the band a roughened surface may be formed on the under-side of the base of the figures as by means of a piece of glass paper or sand paper fixed thereon. 85 The obstacles thus presented hinder the progress of the figures in varying degrees notwithstanding that they are all mounted and move upon the travelling band, and in a similar way the transversely disposed wires hinder the movement of the figures in varying degrees. These wires may be mounted in a series of two, three or more in position between the ridge-shaped obstacles, or again the wires may be disposed slightly 90 above the travelling band and not in contact with it so as to represent hurdles. 95

The spindle of one of the rollers upon which the travelling band is mounted may be provided with a handle by means of which 100 the band may be set into movement. The respective ends of the frame fittings may be provided in imitation of the starting and winning posts of a race-course.

The travelling band may be provided of 105 green or any other colour and the adjacent part of the carrying frame may be also coloured green or any other colour for the imitation of the race-course.

The invention is illustrated in the accom- 110

panying drawings by way of example in which

Figure 1 is a longitudinal section of a toy apparatus constructed according to the invention, the view being taken on the line $x-y$ of Figure 2 which is a corresponding plan.

Figure 3 is a perspective view showing the form of the racing figures used.

As illustrated in the accompanying drawings an endless band a of felt is arranged to pass over two parallel disposed rollers c and d respectively mounted at opposite ends of the supporting frame e . The spindle of the driving roller c is provided with a handle f by means of which the roller c may be rotated and thus movement imparted to the endless band a .

It will be understood that the rollers c and d are mounted to rotate upon their spindles in the side walls of the frame e . The upper part of the endless band is supported upon a board or other surface g which extends between the longitudinal walls of the frame e in a position between the upper and the lower parts of the endless band a and in such position with reference to the upper part of the band that it is supported in a horizontal plane throughout its course from one roller d to the other c . At intervals transversely disposed bars such as h are supported in position upon the supporting surface g and between the longitudinal walls of the frame e so as thus to form obstructions to the straight course of the upper path of the travelling band a and thus to provide obstructions to the forward movement of the racing figures. In addition, however, wires i are transversely disposed at suitable intervals across the space between the longitudinal walls of the frame e and in position immediately over or in contact with the top of the upper part of the travelling band a . These transversely disposed wires i may be provided of any suitable gauge such as that equivalent to a diameter of $\frac{1}{2}$ of an inch.

The racing figures n are provided of a form substantially as illustrated in Figure 3, that is to say with a base j having its forward end k turned upwardly so that the forward part of the figure rests upon the band i at the part j' while in a middle position or towards the rear the base is hollowed out on its under side at l or otherwise formed so

that its rear edge m protrudes downwardly, the figure being thus supported at the part j' and at the rear at m .

The base j is advantageously provided of substantial thickness so that it is relatively heavy and so that thus as the figures ride on to the wires the rear edge m beds into the material of the endless band a in the manner described.

It will be understood that on the figures n being set into the position indicated in Figure 2 the endless band a may be caused to move in the direction of the arrow indicated in Figure 1 and thus the figures may be moved to a varying extent on the rotation of the handle f of the driving roller c .

I claim:

1. A mechanical race game apparatus, comprising a moving band, obstructions transversely disposed to the direction of movement of the said band, said obstructions hindering the movement of objects placed upon the said band, figures for application upon the said band, said figures having bases whose forward parts are curved upwardly and on the underface have a convex curvature and whose rear parts on the under-side are of a concave curvature, whereby the figures are supported upon the convex part of the base and upon the rear edge of the base, substantially as described.

2. A mechanical race game apparatus, comprising a moving band, obstructions transversely disposed to the direction of movement of the said band, said obstructions hindering the movement of objects placed upon the said band and said obstructions comprising transversely disposed bars such as h , figures for application upon the said band, said figures having bases whose forward parts are curved upwardly and on the under-face have a convex curvature and whose rear parts on the under-side are of a concave curvature, whereby the figures are supported upon the convex part of the base and upon the rear edge of the base, substantially as described.

3. A mechanical race game apparatus as set forth in claim 1, wherein the figures are provided with the under-faces of their bases roughened, in the manner and for the purpose substantially as described.

CYRIL FREDERICK BIGMORE.
